WIRE HAND FOR MANNEQUIN

John W. Rigsby, Evansville, Ind., assignor to Merit Clothing Company, Inc., Mayfield, Ky., a corporation of Kentucky

Filed Feb. 7, 1968, Ser. No. 10,476

Term of patent 14 years

Int. Cl. D20—02

U.S. Cl. D80—8

FIG. 2

FIG. 1 is an elevational view of a wire hand for a mannequin showing my new design, the hand being located obliquely at approximately 45° to illustrate the curved configuration, and

FIG. 2 is an elevational view thereof.

I claim:

The ornamental design for a wire hand for mannequin, substantially as shown and described.
